UNITED STATES PATENT OFFICE.

CHARLES L. MICHOD, OF CHICAGO, ILLINOIS.

POST.

1,142,046.

Specification of Letters Patent. Patented June 8, 1915.

Application filed October 29, 1914. Serial No. 839,213.

To all whom it may concern:

Be it known that I, CHARLES L. MICHOD, a citizen of the United States, residing at 538 South Dearborn street, Chicago, in the 5 county of Cook and State of Illinois, have invented a new and useful Improvement in Posts, of which the following is a specification.

My invention relates more particularly to 10 metal posts of the type adapted to be driven into operative position in the ground, though certain features thereof have utility in posts of the type which are designed to be positioned in the ground by preliminarily 15 excavating.

My object is to provide a novel and simple construction of post which cannot, under the conditions to which it is subjected in use, be pulled out of the ground, or have its anchorage impaired and which, in the case of a drive-post, will permit the post to be driven into the ground to the proper position without requiring much labor.

Referring to the accompanying drawing— 25 Figure 1 is a view in elevation of a post of the type adapted to be driven into the ground, the post being shown positioned in the ground. Fig. 2 is an enlarged perspective view of the lower end of the post. Fig. 30 3 is a similar view of a modification of the post of Figs. 1 and 2; and Fig. 4, a section taken at the line 4 on Fig. 3, and viewed in the direction of the arrow.

Referring to Figs. 1 and 2, the post there- 35 in shown is formed of an upright member 5 of metal, as for example, steel, either rigid or flexible, and preferably of L-shape in cross-section, one of the sides of said up- right containing openings 5^a for receiving 40 staples for fastening the wire-fencing in place against said side. The lower ex- tremity up the upright 5 is pointed, as in- dicated at 6, by beveling the sides of the post, as shown, and is provided with anchor- 45 age means. The anchorage means illus- trated comprises two plates secured as by rivets 8 against the outer surfaces of the sides of the upright 5 to extend at angles to each other and form wings 7. These plates 50 are each of general triangular form and are secured to the sides of the upright 5 in such position, as represented, as to cause the long edges of these plates to incline upwardly and away from the upright, thereby produc- 55 ing a structure which may be readily driven into the ground. It is preferred that the

plates forming the wings 7, which prefer- ably are of the same shape and size, be se- cured to the upright 5 in such position that one of these plates will extend a slight dis- 60 tance above the other, as represented in Figs. 1 and 2. It will be understood that if desired the anchorage means for the upright may be formed of a single plate instead of 65 two plates to present the wings 7 disposed at an angle to each other.

In the construction illustrated in Figs. 3 and 4 the wings 7 forming the anchorage means are formed of a single plate instead of two plates. In this case the wings, in- 70 stead of being located one slightly above the other, are secured to the upright 5 at the same elevation, though, if desired, the single plate may be so formed, as will be apparent, that one wing will extend slightly above the 75 other as in the case of the construction illus- trated in Figs. 1 and 2. The securing means for the wings 7 in the construction shown in Figs. 3 and 4 are shown as U-bolts 9 which pass through openings in the wings 7 and 80 carry nuts 10 which bear against the outer sides of the wings, these bolts serving, when the nuts 10 are tightened, to clamp the wings to the upright though it will be understood 85 that any other form of fastening may be em- ployed, if desired.

The provision of wings, as stated, is de- sirable as the action of the same upon the ground in which these wings are completely 90 embedded is such as to cause a relatively large section of ground of general L-shape section surrounding the post at the wings, to resist the pulling of the post out of the ground, which insures rigid anchorage of 95 the post.

It is desirable that provision be made for causing the wings to extend approximately a predetermined distance below the ground level, regardless of the height to which the upright extends, this being especially de- 100 sirable where suddenly hard soils are encoun- tered in driving the post, and to permit this to be accomplished, I provide for the secur- ing of the wings in the case of the construc- 105 tion illustrated in Figs. 3 and 4, at different elevations on the upright.

What I claim as new and desire to secure by Letters Patent is—

1. A post comprising an upright of gen- 110 eral L-shape in cross section and wings fit- ting flatwise against the flanges of said up- right and disposed at an angle to each other.

and arranged in relatively overlapping position, the upper edge of each wing extending at an angle to said upright and the upper edge of one of said wings extending in a plane above the upper edge of the other of said wings.

2. A post comprising an upright, wings fitting flatwise against the sides of said upright, and disposed at an angle to each other and adjustable along said upright, and means for holding said wings in adjusted position on said upright.

3. A post comprising an upright of L-shape in cross section, wings fitting against the flanges of said upright, at its lower end, and U-bolts passing through apertures in said wings and adapted to secure the latter in different positions of vertical adjustment on said upright.

CHARLES L. MICHOD.
